UNITED STATES PATENT OFFICE

155,061

DESIGN FOR A BOTTLE OR THE LIKE

Arthur C. Williams, Washington, D. C.

Application August 2, 1948, Serial No. 147,892

Term of patent 14 years

(Cl. D58—8)

To all whom it may concern:

Be it known that I, Arthur C. Williams, a citizen of the United States, residing at 455 H Street, S. W., Washington, D. C., have invented a new, original, and ornamental Design for a Bottle or the like, of which the following is a specification, reference being had to the accompanying drawing, forming part thereof.

In the drawings:

I claim:

The ornamental design for a bottle or the like, as shown.

ARTHUR C. WILLIAMS.
